Ohio, assignors to George E. Dunstan, Cleve-
land, Ohio

Application July 7, 1944, Serial No. 543,784

3 Claims. (Cl. 255—2)

1

This invention relates to hydraulic ground-piercing machines for forcing a hole horizontally through the ground for the reception of a water pipe or the like and the installation thereof.

The main object of the invention is to provide a machine of said character of great power and efficiency and quick action, which is capable of use in cramped spaces and convenient for transportation to and from the job and into and out of the basement of a building.

Another object of the invention is to provide a machine of the above character, which is easily manipulated or controlled for actuating the piercing rod step by step in either direction.

A further object of the invention is to provide a machine of the above character, which will automatically grip and release the piercing rod for advancing same step by step or for withdrawing the piercing rod from the opening made thereby.

A further object of the invention is to provide a machine of the above character, which is not only capable of providing a hole through the ground by forward piercing action but also for return pulling therethrough for installation therein the water pipe or the like.

With the above and other objects in view and for a clear understanding of the invention, the same will be hereinafter fully described with reference to the accompanying drawings, and the novel features thereof will be particularly pointed out in the appended claims.

In the drawings,

Fig. 1 is a side elevation of a hydraulic ground-piercing machine constructed in accordance with our invention and set up in the basement of a building for piercing a hole through the ground.

Fig. 2 is a plan view of the machine as shown in Fig. 1, the gasoline engine being omitted.

Fig. 3 is an enlarged view of the piercing member attached to the first length of tubing by a coupling.

Fig. 4 is a longitudinal sectional view in elevation of the hydraulic cylinder.

Fig. 5 is an elevation of the box for containing the fluid and for housing and supporting the pump, the relief valve and the control valve together with the piping connecting same, for actuating the hydraulic cylinder, the front side of the box being removed.

Fig. 6 is a plan view of Fig. 5, the top of the box being removed.

Fig. 7 is an enlarged view of the forward end of the piercing rod and chuck for automatically gripping the length of tubing to cause forward movement thereof in the piercing action,

2

Fig. 8 is a similar view to Fig. 7, the collar and slip jaws of the chuck having been reversed for automatically gripping the length of tubing to cause withdrawal movement of same.

Fig. 9 is an end view of the collar and slip jaws of the chuck.

Fig. 10 is a longitudinal sectional view of the control valve, and

Fig. 11 is a plan sectional view taken on line 10—11—11 of Fig. 10.

Referring to the drawings, 1 represents the foundation of a building, 2 the basement floor, 3 the earth around the foundation and 4 a broken out opening through said foundation at the place 15 of beginning for the piercing of the ground. This invention is designed especially to force a hole horizontally through the ground 3 for the purpose of receiving and laying a pipe extending from the water supply line under the street into the basement of the building.

The means for forcing the hole horizontally through the ground consists of a hydraulic cylinder 5 having a forward head 6 and a rear head 7. The heads 6 and 7 are provided with central openings indicated at 8 and 9, in which is slidably mounted a hollow piston rod 10. For preventing leakage around the piston rod 10 at the heads 6 and 7, gland nuts 11 and 12 are provided, and suitable packing 13 therefor. Fixed 30 by cross-pins at 14 or in any other suitable manner to the piston rod 10 for actuating same longitudinally is a piston 15, which is provided with packing rings at 16 to prevent leakage. For actuating the piston 15, fluid under pressure is admitted alternately to each end of the cylinder 35 5 through openings 17 and 18 provided in the heads 6 and 7 thereof. The cylinder 5 is supported by a base 19, which is provided with suitable openings 20 for receiving long pins or bolts as 21 adapted to be fixed well into the ground or solidly into the floor for anchoring said cylinder securely in position.

The hollow piston rod 10 is adapted to receive and impart longitudinal movement to a 45 piercing rod indicated as a whole by 22, which is made up preferably of lengths of tubing 23 by adding length to length as the piercing process progresses as will later be described. To the forward end of the first length of tubing 23 of the piercing rod 22 is secured a suitable pointed member 24 for piercing the ground. The pointed member 24 is threaded at its shank end 25 and removably secured by means of a coupling 26 or in any other suitable manner to the forward projecting and threaded end 27 of the first length 50 of tubing to permit attachment thereof after said 55

length of tubing has been induced through the rear end of the hollow piston rod 10 and also to permit the use of various types of points according to the nature of the ground to be pierced. Each length of tubing 23 is threaded at each end as at 27 and attached to the preceding one by means of a coupling 28, after the latter length of tubing has passed out and beyond the hollow piston rod 10 and the first length of tubing has been induced therein and through said piston rod when in its rear position.

For causing the automatic gripping of the piercing rod 22 by the hollow piston rod 10 when moving in the forward direction for forcing said piercing rod in the same forward direction and automatically releasing said piercing rod upon the return movement of said piston rod for leaving rod in its forward movement position, the following described means is provided. The forward end of the hollow piston rod 10 is threaded at 29 for removable attachment of the cap of a chuck 30 having a bore 31 and a central opening 32 through its outer end for the passage of the piercing rod 22. Arranged in the bore 31 of the cap 30 and held against the end of the hollow piston rod 10 thereby is a collar 33 having an inwardly inclined surface 34 for receiving segmental slip jaws 35 having outwardly complementary inclined surfaces 36 and inside forwardly extending teeth 37 for gripping the piercing rod 22. As the piston rod 10 moves forward, the slip jaws 35 are wedged into engagement with and their teeth 37 dig into the piercing rod 22 thereby causing forward movement thereof. Upon the reverse or rear movement of the piston rod 10, the slip jaws 35 are permitted to move outwardly or radially and thereby release said piercing rod, thus leaving same in its forward movement position. After the piercing rod 22 has by successive forward steps forced an opening through the ground from the basement to the water supply line, the pointed member 24 is disconnected and removed at the coupling 28 and copper tubing or other conduit of the proper length indicated by 38 is secured to said piercing rod by means of said coupling or other suitable means for the purpose of drawing said copper tubing back through the opening made by the piercing rod for installing same in the ground. In order to cause the hollow piston rod 10 to automatically grip and release the piercing rod 22 as already described but in the reverse direction for withdrawing said piercing rod, said hollow piston rod is moved back and forth until the rear end of the last length of tubing 23 of said piercing rod has passed therethrough and is no longer gripped by the slip jaws 35 for imparting forward movement to the piercing rod. Upon the next rear movement of the piston rod 10, the cap 30 will be in spaced relation to the end of the piercing rod 22, whereby said cap may be removed, the collar and slip jaws 35 reversed and said cap replaced. The rearward movement of the piston rod will now cause the slip jaws 35 to automatically grip the piercing rod 22 and thus exert pressure action thereon while the forward movement of the piston rod will cause the slip jaws to release the piercing rod, thereby withdrawing the piercing rod in a step by step movement and at the same operation installing the copper tubing in the ground. When installing the copper tubing 38, the lengths of tubing 23 as same pass successively through and out of the hollow piston rod 10 are detached from each other at the cou-

pling 28 and withdrawn from the rear end of said piston rod.

The means for alternately supplying fluid pressure to the cylinder 5 for actuating the piston 15, first in one direction and then in the other at the will of the operator, and thereby reciprocating the hollow piston rod 10 and thus forcing the piercing rod 22 step by step through the ground, or for withdrawing the piercing rod step by step out from the opening made thereby, will now be described.

A box 39 constructed of plate metal is divided by a horizontal plate 40 forming a lower compartment 41 serving as a fluid tank and an upper compartment 42 for housing and supporting the power producing mechanism and control valve therefor. Arranged transversely of the fluid tank 41 is a diaphragm 43 leaving over-flow space above the top thereof. The top of the box 39 is closed by a cover 44 and bolted thereto at 45 is a gasoline engine 46 having a power shaft 47 carrying a belt-wheel 48, which drives a belt 49 and thereby a wheel 50 fixed to the projecting end 51 of the shaft of suitable pump 52, which is located in the upper compartment 42 of the box 39 and bolted at 53 to the horizontal partition plate 40 thereof. Leading from the fluid tank 41 to the pump 52 is an intake pipe 54 and from said pump an outlet pressure pipe 55 leading into a suitable relief valve 56, which is bolted at 57 to the end of the upper compartment 42 of the box 39. Extending from the outlet of the relief valve 56 to the central inlet port 58 of a suitable four-way control valve 59, which is bolted at 60 to the side of the upper compartment 42, is an inlet pressure pipe 61. Leading from and connecting one pressure outlet port 62 of the four-way control valve 59 to the forward head port 17 of the hydraulic cylinder 5 is a suitable high pressure flexible hose 63, and leading from the connecting another pressure outlet port 64 of said four-way control valve to the rear head port 18 of said hydraulic cylinder is a similar flexible hose 65. The four-way control valve 59 has a longitudinal bore 66 from which extends the central inlet port 58 and the pressure outlet ports 62 and 64, and also a pair of end pressure relief or return ports 67 and 68 connected by a by-pass 69 from which extends a central outlet port 70. A return pipe 71 leads from the port 70 of the four-way control valve 59 to a pressure return pipe 72 leading from the relief valve 56 to the fluid tank 41. For controlling the ports of the four-way valve 59 to direct the fluid pressure to either end of the hydraulic cylinder 5 at the will of the operator, a pair of spools 73 and 74 fixed to a stem 75 are slidably mounted in the bore 66 of said valve, and actuated by means of a lever handle 76, which is pivoted at 77 to a bracket 78 of said valve and to the end of the stem 75 at 79. The handle 76 projects through a suitable slot 80 provided in the cover 44 of the box 39.

In practice, the hydraulic cylinder 5, the box 39 with oil in its lower compartment 41, and the gasoline engine 46 are transported to the job as separate units for convenient handling in and out of a truck and into and removal from a basement. Said units are set up in a basement opposite a broken out portion as at 4 of the foundation as shown, and the engine 46 is started with the lever handle 76 of the control valve 59 in vertical and neutral position to insure no movement of the piston 15 of the hydraulic cylinder 5. To the first length of piercing tubing 23 in-

troduced from the rear through the hollow piston rod 10, and to the forward projecting end thereof is attached the pointed piercing member 24 by the coupling 26. When the engine 46 is in operation and the lever handle 76 is in its vertical and neutral position, the engine drives the pump 52 continuously and causes the oil from the tank 41 to enter the intake pipe 54, flow through the pipe 55, the relief valve 56, and out by way of the return pipe 72 back to said tank. As no pressure is admitted to the cylinder 5, the piston 15 and the piston rod 10 remain stationary.

For admitting pressure from the pump 52 to either end of the hydraulic cylinder 5 for actuating the piston rod 10 longitudinally in either a forward or rearward direction for producing a full or partial stroke thereof at the will of the operator, the lever handle 76 may be moved back and forth in the slot 80 of the cover 44. Depending upon the nature of the ground and the difficulty of penetration thereof by the piercing rod 22, the lever handle 76 may be manipulated to give the piston rod 10 a long or successive short strokes. Assuming that the piston 15 is at the rear end of the cylinder 5, and the operator desires the piercing rod to move forward, the lever handle 76 of the four-way control valve 59 is moved rearwardly, thus actuating the stem 75 and the spools 74 and 73 carried thereby in the same direction and thereby opening the port 64 and admitting fluid pressure from the pump 52 by way of the pipe 55, the relief valve 56 and the pipe 61 to the hose 65 and to the rear end of the cylinder for forcing the piston forward. At the same time that the port 64 is opened, the port 62 is also opened to the bore 66 and the port 67, thereby permitting the escape of the pressure from the forward end of the cylinder through the hose 63 to the by-pass 69 and the pipes 71 and 72 to the tank 41. The forward movement of the piston 15 carries the piston rod 10 in the same direction and this movement causes the slip jaws 35 of the chuck 30 at the forward end of the piston rod to automatically grip the piercing rod 22 and thereby force same forward.

To relieve the fluid pressure at the rear end of the cylinder 5 and direct fluid pressure to the forward end thereof for forcing the piston 15 in the rearward direction, the lever handle 76 is moved forward. This will advance the spools 73 and 74, whereby the spool 74 will open the port 64 to permit escape of the fluid pressure from the rear end of the cylinder through the hose 65, the bore 66, the port 68, the by-pass 69, and the by-passes 71 and 72 to the tank 41, and at the same time, the spool 73 will open the port 62 to admit the fluid pressure from the pump 52 by way of the pipe 61 through the port 58, the bore 66 and the hose 63 to the forward end of the cylinder for forcing the piston rearwardly. Upon the rearward movement of the piston rod, the slip jaws 34 automatically release their grip upon the piercing rod 22 and it remains stationary until the next forward movement of the piston. As the lengths of tubing 23 of the piercing rod 22 are forced step by step through the ground and finally pass one by one beyond the chuck 30 when in its retarded or rear position, other lengths of tubing are attached consecutively to the preceding ones until the piercing rod is the required length for completing the opening through the ground. Upon completion of the opening, the pointed member 24 is detached from the piercing

rod 22, the collar 33 and slip jaws 35 are reversed after removal of the cap 30, and the end of a suitable length of copper tubing to be installed in said opening is attached by a reducer 81 to the coupling 26 of the piercing rod for pulling said copper tubing back through the opening by the reverse manipulation of the lever handle 76 resulting in the reverse operations of those described in piercing the opening.

From the above description and in connection with the accompanying drawings, it is apparent this machine is well adapted for forcing an opening through the ground and the installing of a conduit therein by simple and easy manipulation of a control lever handle, and that it is designed for efficiency and also convenient transportation to and from the job and use in cramped spaces.

Having fully described our invention what we claim is:

1. In a ground-piercing machine, the combination of a cylinder, a piston rod slidably mounted in the cylinder, a piston slidably mounted in the cylinder, the piston being fixed to the piston rod for actuating same, said piston rod being hollow, a piercing rod in said piston rod, means for actuating the piston, a chuck including a cap, the cap being removably fixed to the forward end of said piston rod, the cap having an open end for the passing therethrough of said piercing rod, a collar in and held by said cap, the collar having an inwardly inclined surface, slip jaws having outwardly inclined surfaces arranged in said collar adapted to be forced into gripping said piercing rod upon forward movement of said piston rod and releasing same upon returning movement thereof, and said collar and said slip jaws being adapted to be reversed in said cap for causing the reverse gripping and releasing action to that first mentioned when said piston rod is moving in the rearward direction.

2. In a ground-piercing machine, the combination of a cylinder arranged in a horizontal position, a piston rod slidably in the cylinder, a piston slidably mounted in the cylinder, the piston being fixed to said piston rod for actuating same, said piston rod being hollow, a piercing rod in said piston rod, a pointed member removably attached to the forward end of the piercing rod, means for actuating said piston forward and rearward, a cap removably fixed to the forward end of said piston rod, the cap having an open end, a collar in and held by said cap, the collar having an inwardly inclined surface, slip jaws having outwardly inclined surfaces arranged in said collar for causing the automatic periodic gripping and releasing of said piercing rod upon each movement of said piston rod, which forces said piercing rod horizontally through the ground and then causes the automatic releasing thereof and thereafter causes a further forward advance of the piercing rod to the completion of the pierced opening through the ground.

3. In a ground-piercing machine, the combination of a cylinder arranged in a horizontal position, a piston rod slidably mounted in the cylinder, a piston slidably mounted in the cylinder, the piston being fixed to said piston rod for actuating same, said piston rod being hollow, a piercing rod in said piston rod, means for actuating said piston, a cap removably fixed to the forward end of said piston rod, the cap having an opening for the piercing rod, a collar in said cap, the collar having an inwardly inclined surface, slip jaws having outwardly inclined surfaces ar-

5 ranged in said collar and caused to be forced into gripping said piercing rod upon forward movement of said piston rod and release same upon returning movement thereof for forcing said piercing rod forward horizontally step by step through the ground to pierce an opening for a length of tubing, and said collar and slip jaws being removable and reversable and replaceable as a unit in said cap whereby said automatic gripping and releasing of said piercing rod by said slip jaws is reversed thereby reversing the direction of said step by step forward movement of said piercing rod for installing a length of tubing in said pierced opening.
